Eugene J. Le Claire, St. Paul, Minn., assignor to
Harry F. Joesting, St. Paul, Minn.

Application December 9, 1944, Serial No. 116,822

Term of patent 7 years

(Cl. D44—1)

To all whom it may concern:

Be it known that I, Eugene J. Le Claire, a citizen of the United States, residing at St. Paul, in the county of Ramsey and State of Minnesota, have invented a new, original, and ornamental Design for a Combined Pressure Cooker Door and Securing Apparatus, of which the following is a specification, reference being had to the accompanying drawing, forming part thereof.

Figure 1 is a front elevational view of my com-

bined pressure cooker door and securing apparatus showing my new design;

Figure 2 is a bottom plan view of the same; and
Figure 3 is a side elevational view of the same.

I claim:

The ornamental design for a combined pressure cooker door and securing apparatus, as shown.

EUGENE J. LE CLAIRE.
